Stephen Stafford

UNITED STATES PATENT OFFICE.

STEPHEN STAFFORD, OF CARROLLTON, MISSOURI.

IMPROVEMENT IN HEMP-BREAKING MACHINES.

Specification forming part of Letters Patent No. 26,449, dated December 13, 1859.

To all whom it may concern:

Be it known that I, STEPHEN STAFFORD, of Carrollton, in the county of Carroll and State of Missouri, have made certain new and useful Improvements in Machines for Cleaning and Hackling Hemp; and I do hereby declare that the following is a full, clear, and exact description of the same, reference being had to the accompanying drawings, forming a part of this specification, in which—

Figure 1 is an end view of my machine, and Fig. 2 is a top view of the same.

Similar letters of reference in each of the several figures indicate corresponding parts.

The nature of my invention consists in constructing the brake with two disks or heads and uniting said disks by means of longitudinal rounds or slats armed with obliquely-set teeth, and arranged so that spaces shall exist between them, and they can be adjusted to give the teeth any desired obliquity, in the manner and for the purpose hereinafter set forth.

To enable others skilled in the art to make and use my invention, I will proceed to describe its construction and operation.

A A' is the frame of the machine.

C is the cylinder, which has its bearings at E E in the frame A A'.

H H are bars connecting the cylinder-heads, in which the oblique pins P P are inserted. The teeth or pins P P are situated obliquely to the axis or elements of the cylinder, as clearly shown in the drawings. The bars H H, in which the oblique teeth P P are permanently fixed, can be so arranged and fastened in the circular drum or cylinder that any desirable inclination may be given the teeth. One means of attaining this end is by the employment of set-screws S S, (see Figs. 1 and 2,) which are made to pass through the peripheries of the circular heads, and, being screwed against the bars H H, any desirable obliquity may be given the bars, and consequently to the teeth P P. If the "harp" be too much watered, the teeth can be thus lowered, so as to prevent loss, and if the harp be not sufficiently watered,

the teeth can be raised to expedite the cleaning and hackling.

It is obvious that any similar device for raising or lowering the teeth as circumstances may require may be employed.

D is a wheel situated on the axis of the revolving cylinder, to which the power is applied. The revolving cylinder moves in the direction indicated by the arrow in Fig. 1. The operator stands near the part A' of the frame, and places the hemp upon the revolving cylinder, the teeth P having been adjusted, as described, to suit the condition of the hemp which it is desired to clean and hackle. The inclination of the cleaning and hackling teeth, as shown, enables the operator to clean and hackle the harp without the labor necessarily expended in cleaning and hackling upon the machines ordinarily employed for that purpose. It is obvious that the same end may be obtained as in my invention by the insertion of teeth situated obliquely in a solid drum, in lieu of the bars, which I prefer to employ, and the same result may also be attained by the employment of flat pieces situated on a revolving cylinder, and so shaped or grooved as to perform the same functions as the oblique teeth in my invention, and I do not therefore wish to be restricted to the use of teeth or pins, as shown in my invention, as I deem the modifications I have described as mere equivalents of my invention.

What I claim as my invention, and desire to secure by Letters Patent, is—

Constructing the brake with two disks or heads and uniting said disks by means of rounds or slats armed with obliquely-set teeth, and arranged so that spaces shall exist between them, and they can be adjusted to give the teeth any required obliquity, substantially as and for the purposes set forth.

STEPHEN STAFFORD.
